UNITED STATES PATENT OFFICE.

HENRY A. HOUSE AND HENRY A. HOUSE, JR., OF BRIDGEPORT, CONN.

ELECTRO-PHONETIC TELEGRAPH-SOUNDER.

SPECIFICATION forming part of Letters Patent No. 354,139, dated December 14, 1886.

Application filed August 16, 1886. Serial No. 211,040. (No model.)

To all whom it may concern:

Be it known that we, HENRY A. HOUSE and HENRY A. HOUSE, Jr., citizens of the United States, and residents of Bridgeport, in the county of Fairfield and State of Connecticut, have invented certain new and useful Improvements in Electro-Phonetic Telegraph-Sounders, of which the following is a specification.

Our invention is an electro-phonetic telegraph-sounder, whereby electric currents received by the instrument act upon a sounding-head to produce audible sounds, and whereby the movements of said head produced by sound are the means of transmitting like movements to another head and producing audible sounds therefrom; and our invention consists in the construction of the instrument fully described hereinafter, and shown in the accompanying drawings, in which—

Figure 1 is a longitudinal section of an instrument embodying our invention. Fig. 2 is a sectional plan. Fig. 3 is a perspective view showing a modification, the case removed. Fig. 4 is a perspective view of the case. Fig. 5 is a detached perspective view of sounding head and bar.

The case of the instrument consists of a metallic or other ring, A, partially closed by two wings, between the edges 2 2 of which is an opening, x, and two parallel arms, 3 3, extending from opposite parts of the ring to one side. The ring is threaded internally, or otherwise constructed, for the attachment of a detachable sound-reflector, B, of rubber or other material, 35 in the shape of a ring, screwing into the ring A, and having a flaring mouth, and between the inner end of the sound-reflector and an annular seat, y, on the ring A is confined the edge of a light discular sounding-head, C, a 40 lip, 4, on said head extending into a notch, 5, in the ring A and preventing the head from turning.

Upon one of the arms 3 is supported an electro-magnet, D, which, as shown, consists of 45 two pole-pieces, 6 6, inserted in openings in the arm and surrounded by spools of wire, the opposite ends of the wire being connected to binding-posts 7 7, carried by the opposite arm, 3.

The armature E is a bar pivoted to a stand-

ard, 8, secured to one of the arms 3, and prolonged to form a finger or horn, 9, and the extent of the vibration of the armature on its pivot in both directions is defined by adjustable limiters, and the armature is normally held slightly above and free from contact with the magnets by a spiral spring, 25, passing through the tubular core of the outer magnet and adjusted therein to any desired extent by a screw, 26.

The limiters 12 13 are carried upon a bar or arm, 19, secured centrally to and projecting from the sounding-head C, and, as shown, each limiter consists of a screw or nut carried by the threaded bar 10, and adjustable thereon.

In Figs. 1 and 2 the bar 10 is bent to form two arms, one carrying a limiter-nut, 12, arranged to make contact with the horn 9, and the other carrying a limiter-screw, 13, making contact with the end of the armature. In Figs. 70 3 and 5 the bar 10 is straight and carries two limiter-nuts, and passes through a perforation in the horn 9, the nuts being on opposite sides of the horn. In either case, by properly adjusting the limiters the amount of vibration of the armature may be determined and defined, and in each case there is a direct contact between the armature and limiters—that is, the armature itself or a positive connection thereof has a direct contact with the limiters. When 80 the magnet is charged, the armature is drawn thereto and the horn is brought to bear against the limiter 12, and when the magnet is uncharged the limiter 13 prevents the armature swinging beyond a very limited extent from 85 the magnet. The limiter is connected to the sounding-head at or about its center, and is provided with extended curved bearings in contact with the sounding-head, which tend to stiffen it as it is bent by the limiter or otherwise. When the circuit is closed and the armature has spent its force against the limiter, and the sounding-head is held in magnetic equilibrium, audible sounds of any kind are 90 distinctly received, and may also be transmitted by putting the instrument in circuit with another of like character.

The working parts of the instrument, being wholly supported by the open ring and the separated and exposed arms 3 3, are readily 95 100

accessible; but to protect them from injury we use a cover, 1, consisting of a sheet of flexible metal, rubber, &c., bent to form a back piece, 15, and two side pieces, 16 16, which receive 5 between them the arms 3 3, and completely inclose the devices supported thereby.

The cover may be secured in different ways—one consisting in providing each side piece with a curved lip, 17, which, by pressing the side 16 inward, may be carried into the opening 18, and then engages with the edge 2 and holds the cover in place. The cover may be at once released by pressing the opposite sides toward each other with the thumb and forefinger, to carry the lips away from the edges 2 2.

Without limiting ourselves to the precise construction and arrangement of parts shown, we claim—

- 20 1. An electro-phonetic telegraph-sounder provided with a frame consisting of a ring having a bearing for the sounding-head and two projecting arms supporting the magnet and adjuncts, substantially as described.
- 25 2. The combination, with the frame consisting of a ring and projecting arms, of a cover consisting of a flexible sheet bent to form a back piece and sides inclosing the arms, substantially as described.
- 30 3. The combination of the ring and arms, and cover consisting of a sheet bent to form sides and back piece and provided with lips adapted to engage with bearings upon the frame, substantially as described.
- 35 4. The combination of the frame having a threaded ring, seat 5, and arms, and a sound-reflector screwing into the frame-ring and intermediate sounding-head, substantially as described.
- 40 5. The combination, with the sounding-head and centrally-projecting bar, of the electro-

magnet, armature, and limiters carried by the bar, to directly limit the movements of the armature, substantially as described.

6. The combination of the sounding-head, 45 bar extending therefrom, electro-magnet, pivoted armature extended to form a horn, and limiters carried by the bar to define the movement of the armature, substantially as described.

50 7. The combination of the sounding-head, bar extending therefrom, electro-magnet, pivoted armature extended to form a horn, and limiters carried by the bar to define the movement of the armature, and spring normally holding the armature in an elevated position, substantially as described.

8. The combination of the sounding-head and electro-magnet and armature, and a bar extending from the head, with adjustable bearings directly limiting the movements of the armature, substantially as described.

60 9. The combination of the frame having a ring and parallel arms, sounding-head provided with a projecting bar carrying limiters, 65 electro-magnet carried by one of the arms, and armature arranged to make contact with the limiters, substantially as described.

70 10. The combination of the sounding head, magnet, armature, bar provided with two arms carried by the head, and limiters carried by the bars to make contact with the armature, substantially as described.

In testimony whereof we have signed our names to this specification in the presence of 75 two subscribing witnesses.

HENRY A. HOUSE.
